UNITED STATES PATENT OFFICE.

ALVAH VANDERMARK, OF NEWBURGH, NEW YORK.

WINDOW FIXTURE.

Application filed August 24, 1927. Serial No. 215,142.

The present invention relates to improved window fixtures of the class wherein a series of independent supporting devices are provided for simultaneously suspending a window shade, curtains, and complementary draperies.

The salient and indispensable features of the invention are as follows:

First, due to the adjustable features of the structure it can be used for any size curtains and shade rollers.

Secondly, only four nails are required in fastening the entire fixture on the window.

Third, it fits any window so that no measurements are required before putting it up.

Moreover the curtains and shades can be attached and centered with respect to the window while they are held in place through the medium of the sliding devices.

Finally, the relative adjustability of parts is such as to permit the curtain, draperies and shades to be hung in an expeditious manner.

Other advantages and features of the invention will become apparent from the following description and drawings.

In the accompanying drawings:

Figure 1 is a top plan view of the complete fixture showing the relative position of parts and showing the manner in which it is mounted on the window frame.

Figure 2 is an enlarged end fragmentary view showing the attaching brackets, the curtain support brackets, and the shade roller brackets.

Figure 3 is a longitudinal section taken approximately upon the plane of the line 3—3 of Figure 2.

Figures 4, 5, and 6 are transverse sections taken on the lines 4—4; 5—5, and 6—6 of Figure 2.

Figure 7 is a perspective view of the improved curtain bracket.

Figure 8 is a perspective view of the improved shade bracket.

Referring now to the drawings by numerals, it will be seen that the main supporting member is designated generally by the reference character 9, the same being composed of a pair of telescopically connected sections 10 and 11 and these sections being formed on their longitudinal edges with channel shaped guides. The end portions of the sections are directed outwardly and at substantial right angles as indicated at the points 12. A pair of supporting brackets

13 are provided for fastening these sections in place. Each bracket comprises a metal plate having attaching ears 14 screwed or otherwise fastened to the window frame 15. The plates are provided with substantially 60 tubular guides 16 as shown in Figure 2 to permit sliding motion of the sections 10 and 11 in an obvious manner. Located at each end of the supporting member we find a pair of individual brackets. These brackets are 65 better shown in Figures 7 and 8. In Fig- 7 the bracket 17 is provided for supporting a curtain and is therefore designated as the curtain bracket. It is provided with a right angularly disposed longitudinally 70 bowed portion 18 which is slidably fitted in the guide channel of the aforesaid sections 10 or 11 as the case may be. Closely associated with the curtain bracket we find a shade bracket 19 having a right angularly 75 disposed mounting including separate curved portions 20 and 21 respectively. The curved portion 20 overlies and frictionally engages and holds in place the part 18 of the curtain bracket 17 while the remaining portion 21 is 80 in tight sliding connection with the comple- 85 mental sections 10, as shown in Figure 3.

Obviously the shade brackets 19 are slidably mounted in sections 10 and 11 of the main supporting member 9 as shown in Figure 1, 85 thus permitting the shade roller and shade 90 22 to be suspended therebetween as here shown. The adjustable curtain support 23 is attached to the bracket 17 in an obvious manner. Finally, the drapery support 24 which is also 90 adjustable has its inturned ends connected to the aforesaid end portions 12 of the main supporting member. Thus, it will be seen that I have provided an adjustable main support, attaching brackets therefor provided 95 with guides to permit sliding motion of the sections of this supporting member. The end portions of the supporting member are directed outwardly and this permits the in- turned end portions of the drapery support 100 to be telescopically connected therewith.

It is believed that by considering the detailed description in connection with the drawings, a clear understanding of the construction, method of application, advantages, 105 and features of the invention will be quite clear to persons skilled in the art to which the invention relates. Therefore, a more lengthy description is thought unnecessary.

While the preferred embodiment of the 110

invention has been shown and described, it is to be understood that minor changes coming within the field of invention claimed may be resorted to if desired.

5 Having thus described the invention, what I claim as new is:—

1. In a structure of the class described, a supporting member including a section having longitudinal guide channels, a bracket having a longitudinally bowed foot portion located in said guide channels, a second bracket having a similar longitudinally
- 10

curved foot portion overlying said first named foot portion.

2. In a structure of the class described, a curtain bracket provided with a right angularly disposed longitudinally bowed flexible foot portion, a complementary shade bracket provided with a portion having curved ends one end of which is adapted to overlap the curved foot of said first named bracket.

In testimony whereof I affix my signature.

ALVAH VANDERMARK.
